GRATER

Stephen A. Mischanski, Wallington, N. J.

Application January 7, 1932. Serial No. 585,345

1 Claim. (Cl. 146—179)

An object of the invention is to provide a grater having a body with a cutting surface and a box for the material to be grated, the box having an opening at the cutting surface, so that, when the box is moved across the cutting surface, the material in the box will be acted on by the said cutting surface.

Another object of the invention is to provide guide means between the box and the body having the cutting surface for directing the path of movement of the box relatively to the body.

Still another object of the invention is to provide the box with openings at its top and bottom, so that the material in the box which is to be grated may be disposed against the cutting surface at the opening in the bottom of the box and be pressed against the said cutting surface by a presser member which is disposed through the opening in the top of the box. It will be understood that the body having the cutting surface may be held with one hand of the operator and a handle on the presser member may be held by the other hand of the operator, so that the hand holding the handle on the presser member may not only press the presser member down against the material to be grated, but may, at the same time, reciprocate the presser member relatively to the body having the cutting surface. The engagement of the presser member with the inner sides of the box will reciprocate the box with the presser member carrying the material to be grated against the cutting surface.

A further object of the invention is to provide the body with a detachable cutter member, so that any desired cutter member may be readily adjusted in position on the body and a worn cutter member may be replaced.

Additional objects of the invention will appear in the following specification in which the preferred form of the invention is described.

In the drawing similar reference characters refer to similar parts in the several views, of which Figure 1 is a plan view of the grater,

Figure 2 is a sectional view on the line 2—2 of Figure 1, and

Figure 3 is a sectional view on the line 3—3 of Figure 2.

By referring to the drawing it will be seen that the grater is provided with a body 5 having its sides 6 bent around the parallel side portions 7 of a rod 8, the rod 8 being bent at 9 at one end of the body 5 to form a handle, the terminals 10 of the rod at the other end of the body serving as supporting legs. The central portion of the body has an opening, as shown at 11, there being

flanges 12 which extend inwardly at the sides of the body at the said opening 11. There is also a flange 13 which extends inwardly at one end of the opening 11 and a flange 14 which extends from the body inwardly at the other end of the opening 11. These flanges 12, 13 and 14 are provided for supporting the ends and sides of a cutter member 15, which is normally disposed on the said flanges, it being understood that any desired cutter member 15 may be mounted on the body 5 at its opening 11 and that the cutter member may be replaced by another cutter member when the cutter member, which has been employed, has become worn, or when another type of cutter member may be used advantageously. It will be understood that, while a particular type of cutter member 15 is shown in the drawing, any other cutter member with projections, teeth or knives may be employed. The cutter member 15 has a tongue 16 which is disposed under the flange 14 at one end of the body 5, there being a pivoted flange 17 on the cutter member 15 which may be turned under the flange 13 to hold the cutter member in position relatively to the body 5.

It will be understood that the body 5 is braced by the parallel side portions 7 of the rod 8 and that the body 5 is also preferably disposed around a rod 18 at one of its ends, which serves to reinforce the body. A rod, similar to the rod 18, may be disposed at the other end of the body, and the body may be turned around this second transverse rod, should this be found to be advisable to strengthen the body.

The sides 6 of the body 5, which are bent around the parallel side portions 11 of the rod 8, serve as guides for the guide members 19 on a box 20, the said box 20 being open at its bottom 21 and also at its top 22, so that material or an article, which is to be cut or grated and which is shown in dotted lines at 23 in Figures 2 and 3, may be disposed in the box 20 against the teeth 24 on the cutter member 15, which, when the box 20 is reciprocated on the body 5, will serve to move the box 20 so that the material or article 23, which is to be cut or grated, will be moved against the teeth 24 on the cutter member 15. As a means to reciprocate the box 20 relatively to the body 5 and also to press the material or article down against the teeth 24, a presser member 25 is provided, this presser member being introduced in the box at its top 22, the presser member having a handle 26 which may be held by one hand of the operator, while the other hand of the operator holds the handle 9 to permit the reciprocation of the box 20 by means of the en-

gagement of the presser member 25 at the inner sides of the box, while, at the same time, the presser member 25 is pressed against the material or article 23 to press or force the same against 5 the teeth 24 on the cutter member 15.

As will best be seen by referring to Figure 2 of the drawing, the presser member 25 has depending teeth 27 which are formed by cutting and pressing portions of the presser member downwardly, these teeth 27 engaging the material or article 23 and serving to hold the same relatively to the presser member 25 and the box 20 as the box 20 is reciprocated over the teeth 24 of the cutter member 15.

15 The upper portions of the sides of the box 20 are turned over a rod 28 which is bent around the top of the box and which serves to reinforce the box, the box also preferably having transverse rods 29 at its bottom, against which the ends of 20 the box are turned. While the upper portions of the sides of the box 20 are turned outwardly around the rod 28, the lower portions at the end of the box are turned inwardly around the transverse rods 29, which serves to check the downward movement of the presser member 25.

It will be seen from the above that the grater,

which is the subject matter of this application, may be manufactured inexpensively and that it may be conveniently used to cut or grate materials and articles of various kinds.

What is claimed is:

In a grater, a rod bent between its ends to form a handle and with parallel sides, a body spaced from the bent portion of the rod with the sides bent around the parallel sides of the bar, the body having a central opening with side and end flanges extending into the opening below the plane at the top of the body to form a seat, a cutter member having sides and one end disposed on the side flanges and one of the end flanges, the cutter member having a tongue disposed under the other end flange, a flange pivoted under the said end of the cutter member for engaging the under side of the adjacent end flange of the body, a box open at top and bottom and having sides the bottoms of which are bent around the sides of the body at the parallel sides of the bar and which slide thereon, and a presser member disposed in the box for pressing material in the box against the cutter member.
